UNITED STATES PATENT OFFICE.

WILLIAM W. DAVIS, OF BALDWIN, MICHIGAN, ASSIGNOR OF ONE-HALF
TO GEORGE F. DUFFING, OF BALDWIN, MICHIGAN.

HYDROCARBON TIRE-HEATER.

SPECIFICATION forming part of Letters Patent No. 718,567, dated January 13, 1903.

Application filed June 19, 1902. Serial No. 112,388. (No model.)

To all whom it may concern:

Be it known that I, WILLIAM W. DAVIS, a citizen of the United States, residing at Baldwin, in the county of Lake and State of Michigan, have invented a new and useful Hydrocarbon Tire-Heater, of which the following is a specification.

This invention relates to devices employed for heating vehicle-tires; and it has for its object the production of a device wherein liquid fuel is used as the heating medium.

The invention consists in a series of independently-controlled segmental burners concentrically disposed and supported upon a frame, which also serves as a support for the tire while being heated.

The invention further consists in certain novel features of construction, as hereinafter shown and described and finally pointed out in the claims.

In the accompanying drawings, Figure 1 represents a plan view of the device complete. Fig. 2 represents a sectional side elevation thereof. Fig. 3 represents an enlarged sectional detail of one of the burner-segments.

The same reference-numerals indicate corresponding parts in all the figures.

The device as illustrated comprises a central receiver 10, into which the liquid fuel is fed through the pipe 11, having a controlling-valve 12 and leading from a suitable reservoir, here shown as a tank 13, provided with a nipple-valve 14, through which compressed air may be supplied to the tank to produce a force feed to the burners when necessary.

The receiver 10 is preferably tubular and disposed in a vertical position, and, as shown, is composed of a section of tubing closed at the lower end and having a screw-cap 30 forming the closure at the upper end, with the feed-pipe 11 leading downwardly through the center of the cap. Radiating from the receiver at equidistant points are pipes 15, of which any desired number may be employed, four being here shown. Branch pipes 16 are mounted for longitudinal adjustment on the pipes 15, preferably by means of expansion-joints, as 17, of the ordinary construction, which permit the longitudinal extension and adjustment of the pipes 16 with relation to the pipes 15. Rising from each of the pipes 16

are spaced upwardly-extending branches, as 18 28, and each of said branches is provided with a segmental horizontally-disposed burner 19, formed of segmental tubes having small 55 needle-like apertures preferably in their outer surface, the apertures being indicated at 20 27, respectively. These apertures may, however, be placed on the inner side of the burners when desired, as shown at 27' in Fig. 3. Each 60 of the branches 18 28 is supplied with a controlling-valve, as 31 32, respectively, so that each burner may be independently controlled to regulate the amount of heat applied to various parts of the tire. The burners are so 65 disposed that when adjusted to their innermost positions their adjacent ends will be nearly or quite in contact, thereby forming two complete spaced circles or circular burners with the flames burning outwardly through 70 the apertures, the degree of heat to be applied to various parts being under the control of the operator.

The radii of the inner set of segmental burners correspond to the smallest size of 75 tire which it is designed to heat, and the radii of the outer sets correspond to the tires of the rear wheels of the same vehicle to which the smaller tires belong, so that both sets of tires may be heated at the same time, if desired. The device is capable of being adjusted to fit any size of tire by means of the longitudinally-adjustable branch pipes 16, the piping, valves, and burners being of any required size to adapt them to all sizes of tires. 85

Disposed beneath the radiating pipes 15 is a supporting annular frame 21, having legs 22, connected intermediately of their length thereto and extended downward to the supporting-surface on which the device rests, the 90 upper ends thereof being turned outward, forming horizontal members 22' for engagement with the under surfaces of the burners 19, and the outer ends of the members 22' are bent downwardly, forming legs for engaging the supporting-surface. By this means the whole device is firmly supported and braced, the band member 21 supporting the radiating pipes 15, the leg members 22 supporting the band member 21, and the horizontal members 22' supporting the burners and the tire to be heated, at the same time leav-

ing the burners free to be adjusted longitudinally without disturbing the tire being treated. The horizontal members 22' also serve to support the outer ends of the extension-pipes 16 through the connecting vertical branches 18, having the burners 19 connected thereto and resting on said horizontal members, so that the expansion-joints 17 are relieved from any lateral strain which would otherwise have a tendency to twist the expansion-joints and cause them to leak.

The whole device is compact and interdependent and readily adjustable to fit various-sized tires, each set of burners being independent from all the others and each burner individually independent by reason of its independent controlling-valve.

By so constructing the device any one burner or series of burners may be used or shut off as desired, so that any particular part of a tire or nest of tires may be heated to a higher degree than the other parts.

The central reservoir 10 is heated by a torch, lamp, or other suitable means when the apparatus is first started to cause the hydrocarbon fed thereto to vaporize therein, so that the fuel so vaporized will escape from the burners in condition to be ignited, and after the burners are heated sufficiently to vaporize the fuel as it passes through them the device becomes self-acting.

I claim as my invention—

1. In a device of the class described, a receiver for the liquid fuel, pipes radiating from said receiver, branch pipes mounted for longitudinal adjustment on said radiating pipes, burners carried by said branches, controlling-valves in said branches, and an annular supporting-frame engaging said radiating pipes.

2. In a device of the class described, a receiver for the liquid fuel, pipes radiating from said receiver, branch pipes mounted for longitudinal adjustment on said radiating pipes, burners carried by said branch pipes, controlling-valves in said branch pipes, an annular supporting-frame having a rest for said radiating pipes, and supporting-legs extending from said annular frame beneath said segmental burners and affording supports there-

for and for the article being heated.

3. In a device of the class described, a re-

ceiver, pipes radiating from said receiver, branch pipes mounted for longitudinal adjustment on said radiating pipes, segmental burners carried by said branch pipes, a central frame supporting said receiver and radiating pipes, extension-frames engaging said central frame and supporting said burners and the branch pipes connected thereto and also supporting the article being heated.

4. In a device of the class described, a receiver, pipes radiating therefrom, branch pipes mounted for longitudinal adjustment on said radiating pipes, spaced pipes extending upwardly from said branch pipes, segmental burners carried by said upwardly-extending pipes, each of said upwardly-extending pipes having a controlling-valve for regulating the supply of fuel to the burner carried thereby.

5. In a device of the class described, a receiver, a feed-pipe leading thereto, a controlling-valve in said feed-pipe, pipes radiating from said receiver, branch pipes mounted for longitudinal adjustment on said radiating pipes, segmental burners carried by said branch pipes and disposed concentrically to said receiver, independent controlling-valves in said branches, an annular frame supporting said radiating pipes, vertical legs engaging said annular frame and having radially-extending members for supporting said burners and the article being heated thereby.

6. In a device of the class described, a receiver, pipes radiating therefrom and having burners connected therewith, and an annular frame supporting said radiating pipes, supporting-legs connected to said annular frame intermediately of their length and having radially-extending members at their upper ends forming a support for said burners and for the article to be heated, and members extending downwardly from the outer ends of said radial members and adapted to engage a supporting-surface.

In testimony that I claim the foregoing as my own I have hereto affixed my signature in the presence of two witnesses.

WILLIAM W. DAVIS.
